INVENTOR:

Pablo Paris,

By his Attorney, Wm. H. Reid.

UNITED STATES PATENT OFFICE.

PABLO PARIS, OF NEW YORK, N. Y.

TYPE.

1,255,216.

Specification of Letters Patent.

Patented Feb. 5, 1918.

Application filed February 23, 1917. Serial No. 150,233.

To all whom it may concern:

Be it known that I, PABLO PARIS, a citizen of the Republic of Venezuela, and resident of New York city, in the county of 5 New York and State of New York, have invented certain new and useful Improvements in Type, of which the following is a specification.

This invention relates to an improved 10 form of type for use in printing generally, but especially adapted for use in connection with type setting machines, particularly those operated by a key-board to set up type for the class of machines that produce fac- 15 simile letters, and which are sometimes known as multigraph machines. One of the objects of the invention is to provide a form of type that can be readily carried or supported in a suitable type tube in a series, 20 adapted to be placed in a type setting machine, wherein upon the type being advanced by suitable selecting means, it will be very easily inserted in a platen or form, by the selecting and advancing means.

25 A further object of the invention is to provide a special form of type whereby one of its sides will be engaged by a special form of type tube, to retain the type in the tube with the character-bearing side separated 30 from the adjacent wall of the tube, to protect the character. A further object is to provide such a form of type with a channel 35 on one side face, to facilitate the separation of the type, and advancement when placed in a series, in a type-setting machine.

Another object of this invention is to provide an improved form of type tube, especially adapted to engage and retain the said form of type.

40 In the accompanying drawing showing embodiments of my invention, Figure 1 is a perspective view of the type. Fig. 2 is a side elevation of the type. Fig. 3 shows in perspective the type tube containing the 45 type. Fig. 4 is an end elevation of the type and type tube; Fig. 5 is a front elevation of the type and type tube, with one end of the tube partly broken to show the type, and Fig. 6 shows the type as held in a special platen.

50 As set forth in the drawing, the type has the character-bearing end 7, containing any desired character, preferably in relief, such as the letter "I" as shown at 8. The end 55 opposite the type-bearing end, is made of

wedge form, preferably having a beveled face, as shown at 9.

The type is provided on one face with a groove at an intermediate part, extending transversely across the type. As shown the 60 type extends rearward from the character-bearing end 8, in a rectangular form, as at 10, and a transverse groove 11 is provided on this face. The beveled face 9 preferably extends up to the groove 11, and as shown, 65 is of less thickness adjacent the groove than the said rectangular portion 10 of the type body. The two opposite sides 12 and 13 of the type body are preferably parallel and perpendicular to the flat bottom wall 14 of 70 the type. But the end 15 of the wedge portion is preferably slightly rounded-off as shown and for this purpose the bottom wall 14 is curved up slightly at this end.

A special form of type tube is designed to 75 form a holder for this form of type, and as shown is formed of a strip of sheet metal of tubular shape, that is bent over and has the longitudinal edges separated. This type tube has a flat wall 16 on one side, with one 80 of the sides bent back, as at 17, at an angle somewhat similar to the angle of the wedge end of the type; and the edge portion of this bend is turned downward toward the wall 16 at an abrupt angle, as indicated at 85 18. The purpose of this bend 18 is to enter the groove 11 in the type, and as the type tube is of spring metal, this will serve to press the flat bottom face 14 of the type, against the wall 16 of the tube, as best 90 shown in Fig. 4. It will be noted that the bend 18 extending into the groove 11, serves to hold the beveled wall 9 slightly offset from the adjacent wall 17 of the type tube.

At the opposite side of the type tube, it is 95 first bent upwardly as at 19, and then bent over parallel with the base 16 to form a top wall 20. It will be observed from Fig. 4 that the upright wall 19 is slightly offset from the character on this end of the type, 100 and the top wall 20 may also be spaced from the opposing face of the type. This is caused by the bend 18 of the type tube being pressed into the transverse groove 11 of the type body, and held there by the resiliency 105 of the tube. This will serve to thoroughly protect the character on the end of the type from damage by engagement with the wall of the type tube, not only while being carried in the type tube, but when advanced 110

longitudinally to fill the tube, and also to remove the type from such holder into the type-setting machine, or other place of use.

It will be seen from Figs. 3 and 5 that these type are placed in a series in the type tube, and are put in one end and slid along through the tube. For the purpose of retaining the type from endwise movement except when desired, I provide a spring strip 21 secured to the outside of the top wall 20, with the end portion 22 extending downward through an aperture 23 in the tube. The projecting portion will engage the end type as indicated in Fig. 5 and prevent its removal from the tube. When it is required to take out the type the strip is bent upwardly, and slightly turned to hold it out of the tube as indicated in Fig. 5.

Where type of this character are placed in a series, in a type-setting machine, it is often desirable to cause the type to be placed endwise, in a tubular holder, to feed the end type successively into a guide-way for the purpose of advancing the same to a platen or form. Such type are sometimes controlled by means of a slide that engages the end type, and prevents its advancement except at the proper stage. To facilitate such operation I provide the type with a channel or slot 24 on one side, that is shown as beveled, the bottom of the channel extending up to merge into the side wall. This will facilitate the entrance of a beveled retaining bend, between each adjacent type.

In Fig. 6 is shown a portion of a special platen or holder, in which a number of angle plates 26 are placed in a frame 25 and have a small hook 27 arranged to enter the groove 11 in the type. These angle plates move upward when the beveled end 9 of the type is inserted to permit the hook portion of the plate to enter the groove. This will also permit removal of any individual type by simply grasping the type and drawing it forward, as the hook portion will release the type at the groove.

Having thus described my invention, what I claim is:—

1. A type having the end opposite the

character-bearing end, of wedge form, and provided with a transverse groove at the middle part of one side only, which groove extends parallel with the edge of the wedge.

2. A type having the end opposite the character-bearing end, of wedge form, and provided with a transverse groove at the middle part in one side with the latter extending to the wedge in a continuous curve, the side opposite the grooved side extending in a plane unbroken surface.

3. A type having a sharp wedge end, one side extending in a plane unbroken surface to the wedge end, the opposite side having a transverse groove at the middle part, said grooved side being beveled from the groove to the wedge end of the type.

4. A type having one side extending in a plane unbroken surface, the opposite side having a transverse groove at the middle part, said grooved side being beveled from the groove to the rear end of the type to provide a sharp wedge, the beveled portion adjacent the groove being of less thickness than the type beyond the groove.

5. A type having one side extending in a plane unbroken surface, the opposite side having a transverse groove at the middle part, said grooved side being beveled from the groove to the rear end of the type, the type being provided with a slot on one side extending up from the bottom edge.

6. A type having one side extending in a plane unbroken surface, the opposite side having a transverse groove at the middle part, said grooved side being beveled from the groove to the rear end of the type, the type being provided with a slot on one side extending up from the bottom edge with the bottom beveled up from the base to merge into the side face.

7. A type member provided with a slot on one side extending up from the bottom edge with the bottom beveled up from the base to merge into the side face, and the latter having a comparatively narrow groove and beveled downwardly to form a sharp wedge.

PABLO PARIS.
